UNITED STATES PATENT OFFICE.

HENRY E. WERNER, OF HOUSTON, TEXAS.

COTTON GIN.

Application filed May 24, 1921. Serial No. 472,220.

To all whom it may concern:

Be it known that I, HENRY E. WERNER, a citizen of the United States, residing at Houston, in the county of Harris and State 5 of Texas, have invented certain new and useful Improvements in a Cotton gin, of which the following is a specification.

This invention relates to new and useful improvements in a cotton gin.

10 One object of the invention is to provide a cotton gin of the roller type whereby the lint is stripped from the seed by the combined action of a friction roller co-acting with a stripper bar.

15 Another object is to provide a roller gin equipped with a roller and a co-acting stripper bar and embodying a construction, and means, whereby the seed cotton is held by air suction against the roller in a zone 20 of the roller adjacent the bar to insure the efficient co-operation of said roller and bar; and the lint is thereby completely stripped from the seed without crushing the seed or injuring the lint.

25 A further object resides in the provision of means for the agitation of the seed cotton and seed adjacent said bar to prevent the congestion thereof and to insure the rotation of the seed so that all of the lint adhering to 30 the seed will be presented to roller and bar, thus insuring the complete and uniform removal of all the lint.

A still further feature resides in the provision of means for conveying away the lint 35 after it has been removed from the seed, as well as the seed itself.

Another novel feature embodied in the invention consists in the improved construction and economical arrangement of the end 40 frames and connecting breast provided with a suction conduit terminating in nozzles for removing the lint.

A further improvement lies in the construction of a ginning roll so formed that 45 the air suction is created diametrically through it, instead of being taken through the end bearings with the result that the journals may be made much smaller thus lessening friction and rendering the adjacent 50 parts more accessible.

With the above and other objects in view, this invention has particular relation to certain novel features of construction, operation and arrangement of parts, an example 55 of which is given in this specification and

illustrated in the accompanying drawings, wherein:—

Figure 1 shows a front elevation of the gin.

Figures 2 and 3 show side and end view, 60 respectively, of the agitating mechanism.

Figure 4 shows a plan view, with certain parts removed for the sake of clearness.

Figures 5 and 6 show side and end view, 65 respectively, of a suction nozzle employed in this form of the gin.

Figure 7 shows an enlarged fragmentary sectional view taken on the line 7-7 of Figure 1.

Figure 8 shows an end view, partially in 70 section.

Figure 9 shows a front view of a modified form of the same type of gin.

Figures 10 and 11 show side and end views, 75 respectively, of the agitating mechanism employed in this form.

Figures 12 and 13 show fragmentary side and end views, respectively, of the type of suction nozzle employed in this form.

Figures 14 and 15 show side and end 80 views, respectively, of a partition employed.

Figure 16 shows a plan view of this form of gin, showing certain parts removed for the sake of clearness.

Figure 17 shows an end view of one of the 85 rollers employed, with the end nut and outer shell removed.

Figure 18 shows a side view of the roller shaft.

Figure 19 shows an enlarged fragmentary 90 transverse sectional view of this type of gin.

Figure 20 shows an end view thereof.

Figure 21 shows a front view of still another form of this type of gin.

Figure 22 shows a partial plan view thereof, with certain parts removed for the sake of clearness.

Figures 23 and 24 show, respectively, side and end views of the agitating mechanism 100 employed in this form.

Figure 25 shows an enlarged fragmentary cross sectional view of this form.

Figure 26 shows an enlarged fragmentary partial sectional view of the form of roller 105 employed in the form.

Figure 27 shows a cross sectional view of said roller, and

Figures 28 and 29 show an enlarged fragmentary partial sectional view and a cross 110

sectional view, respectively, of another type of roller employed in this form.

Referring now more particularly to the drawings, wherein like numerals of reference 5 designate similar parts in each of the figures, the numeral 1 designates the base of the supporting framework, and mounted on this base are the legs 2, 2 and 3 connected by suitable webs, all forming the framework. In 10 the form shown in Figures 1-8 there is a surrounding hood 4 arcuate in cross section, whose ends are fastened to the respective legs 2, and enclosed within this hood there is a fan 5 which is fastened on the shaft 6. This 15 shaft is rotatable in bearings carried by the respective legs 2, 2 and 3 and has a pulley 7 fixed thereon, through which it is driven.

Located above said hood are the ginning rollers 8, 8. These rollers are between the 20 legs 2, 2 and have reduced ends forming sleeves 9, 9, which rotate in the bearings 10, 10 formed in the respective legs 2, 2. The sleeves 9 receive the connected nozzle pipes 11, 11 which extend therethrough and which, 25 at their union, are connected to a common suction pipe 12. Each roller 8 is hollow and formed with lengthwise rows of perforations 13. Within each roller the corresponding pipe 11 is formed into a long suction nozzle 14, said nozzles fitting closely against the inner surfaces of the rollers 8 and the contacting end of the nozzle is formed to conform to the contour of the roller wall against which it fits. The nozzle outlet is a long narrow slit 15 on opposite sides of which are 30 the packing elements 16, 16.

The sleeves 9, at one end, are extended beyond their bearings 10 and have the bevel gear wheels 17, 17 fixed thereon, and beyond these there are the intermeshing spur gear wheels 18, 18 also fixed on these ends of the sleeves. One of said sleeves also carries the 40 fixed pulley 19, over which a suitable belt, (not shown) operates to drive the rollers. 45 These rollers rotate in the directions indicated by the arrows in Figure 7.

A stripper bar 20 is arranged approximately tangential to each roller. This bar is blade-like in form, that is, it is formed 50 with a comparatively sharp edge adjacent the roller. Each blade is fastened to the breast 21, which is formed with bearings 22. These bearings work on a bearing rod 23 carried by the legs 2, 2. Bolted upon the upper sides of the breasts 21, are the bearing plates 24 and 25, whose contacting faces have the long coinciding grooves, forming a long bearing 26 square in cross section and mounted upon the plates 25 are the brackets 27, 55 which have the aligned bearings 28, also square in cross section. Mounted in these respective bearings 26 and 28 are the finger bars 29 and 30, which are connected at one end by a yoke 31. These finger bars are of a 60 form to conform to the contour of the bear-

ings 26 and 28, in which they are mounted to reciprocate, and they have the fingers 32 and 33 secured thereto and arranged in staggered relation, which project out toward the corresponding rollers above the respective 70 bars 20.

In mesh with the respective bevel gear wheels 17, 17 are the pinions 34, 34, which are fixed on crank shafts 35, 35. These shafts rotate in the bearings 36, 36, which are carried 75 by the adjacent legs 2, 2. The shafts 35 are formed with cranks 37, 37, on which one end of the respective connecting rods 38, 38 have bearings and the other ends of these rods are connected to the corresponding yokes 31, 80 31. As the pinions 17 rotate the finger bars 29 and 30 are rapidly reciprocated.

The seed cotton is delivered to the rollers 8 from a suitable delivery chute (not shown) and falls onto, and is separated by, the deflector 39. Approximately equal quantities 85 of the seed cotton is thus delivered to the respective rollers. The cotton is carried round by the rollers toward the stripper bars 20. It is to be noted that the nozzles 14 are 90 slightly above, or in advance of said bars so that said cotton will come within the suction zones just before reaching said bars, and the suction will cause the cotton to adhere to rollers and the fiber will pass between the 95 rollers and bars, but the seed will be arrested by said bars. Meanwhile the agitating fingers 32 and 33 are reciprocating to prevent the congestion of the seed cotton, and seed, 100 against said bars, and the seed are thereby constantly turned so that all sides will be presented to the bars to the end that the lint will be entirely stripped therefrom. The freed seed then fall down the seed chutes 40 and into a suitable container or conveyor. A 105 conventional form of screw conveyor, as 41, may be provided, if desired.

The lint passes on around the rollers and into the lint flues 42, 42 underneath, which unite into a common flue 43. The flue 43 is 110 equipped with a suitable suction fan 44, by means of which a suction is created through said flues to deliver the cotton to any point desired.

The bars and agitating means are carried, 115 as shown, upon the breasts 21. These may be adjusted to regulate the position of the bars and said agitating means, relative to the rollers. This adjustment is accomplished by means of adjusting bolts 45, 45, which 120 pass through the lateral lugs 46, 46, formed on the ends of the breasts 21, and are threaded into the framework.

In the form shown in Figures 9 to 20 inclusive, the type of framework is modified 125 in that the legs 3, 3 are not employed. In this form the rollers consist of the tubular shells 47, 47, which have slightly spiralled rows of perforations 48. The shell is fitted closely over a mandrel 49 whose ends are re- 130

duced forming in effect a shaft 50. The mandrel has lengthwise grooves 51, slightly spiralled, which register with the corresponding rows of perforations 48. The mandrel 5 has a plurality of diametrical bores 52 connecting the diametrically opposite grooves, as shown in Figures 17, 18 and 19.

Mounted between the rollers, and above them there is a suction nozzle 53 whose ends 10 are anchored to the framework and leading from one end of which there is the suction pipe 54. This nozzle is of an elongated tubular form and it fits into a seat 55, arranged underneath it, preferably 15 formed of leather or similar material. This seat has the lateral wings which fit against the rollers and conform to the contour thereof. These wings are backed by metallic plates 56 and are held yieldingly against 20 said rollers by pressure springs 57, which are seated in the nozzle 53. A vertical partition plate 58 is bolted to the underside of the nozzle and said leather seat is clamped between them, and secured to the 25 lower edge of this partition there is a diaphragm 59, of leather or other similar material, U-shaped in cross section and whose edges are turned up between the rollers, as shown in Figure 19. These leathers 30 enclose between them a long chamber 60, which is separated, as shown in said figure, into two lengthwise compartments and the nozzle has a plurality of ports 61 leading from said chamber. The partition 58 has 35 notches 62 in its upper edge which register with said ports and permit air to be drawn from either of said compartments through said nozzle. By this construction suction will be created through the bores 52, successively, as the rollers rotate and bring the 40 bores into communication with the respective compartments of the chamber 60. When in this position the other ends of said bores will create a suction through the opposite perforations 48 just above the stripper bars to hold the seed cotton closely 45 against the rollers until it is brought within range of the stripper bars.

In this form one end of one of the shafts 50 has the band wheel 63 fixed thereon and also has the spur gear 64 which is in mesh with a corresponding gear 65 fixed on the corresponding end of the other shaft 50. The opposite ends of said shafts have the 55 bevel gears 66, 66, fixed thereon which mesh with the pinions 67, 67, which are fixed on crank shafts 68, 68 and are operatively connected with, and reciprocate, the bars 29 and 30 in the same manner and for the same 60 purpose hereinbefore set forth.

In this form of gin the breasts 69, 69 are stationary and adjustably mounted on them are the bar plates 70, 70, to the inner edges of which said bars are secured. The plates 65 24 and 25 are supported on said bar plate

and carry the finger bar which are slidably mounted, as hereinbefore set forth.

Underneath the gin there is an air blast pipe 71 which extends upwardly and branches, forming flues 72, 72, which lead 70 through the breasts and have the long blast nozzles 73, 73, which discharge blasts of air into the enclosed chamber 74, underneath the rollers and leading from which there is a discharge conduit 75. The current of air catches up the lint by suction and frees it from the rollers and delivers it out through said conduit. 75

In Figures 21 to 29 inclusive, the chief modifications of the form shown in Figures 9 to 20, inclusive, consists in the specific construction of the rollers and the agitating means. 80

In this form a rocker shaft 76 is mounted in bearings 77 mounted on the plate 24 and slidably mounted in this shaft there is a reciprocating finger bar 78 which carries the agitating fingers 79. The rocker shafts 76 carry, at one end, arms 80, whose free ends have rollers 81 which are successively actuated by cams 82, carried by the inner faces of the spur gears 64; 65 and the fingers are thereby reciprocated up and down. The opposite ends of the bars 78 are connected, by ball and socket joints, to the respective 90 connecting rods 88, through which they are reciprocated back and forth as hereinbefore stated to agitate the seed and seed cotton to prevent the congestion thereof adjacent the stripper bars, and also to assist in separating 95 the seed from the lint. 100

Two types of rollers are employed in this form of the gin, indicated, respectively, by the numerals 83 and 84. The roller 83 consists of a drum fixed on the shaft 85. This drum has a plurality of lengthwise bores 86 and leading out from these bores are the respective ports 87 arranged in lengthwise rows. The ends of the bores are closed in any suitable manner and the opposing bores are connected by one, or more, cross conduits 88, which lead diametrically through the drum, but separate into grooves around the central shaft, as shown in Figures 25 and 26. The roller 84 is constructed practically the same as the type illustrated by the roller 83, the exception being that the cross conduits 88 are connected around the shaft 85 by means of annular channels 89. 110

In the construction of all of the rollers the formation is such that the suction zone will be confined to their surface immediately in advance of the stripper bars, thus holding the seed cotton close to the rollers at the point of operation of said bars. 120

What I claim is:—

1. A cotton gin including a supporting frame, a roller mounted thereon; an unyielding adjustable stripper bar having a beveled edge arranged tangent the roller, 130

reciprocating fingers pointing toward the roller and lying in a plane passing approximately through the roller axis, said fingers being movable lengthwise with respect to 5 the roller and cooperating with the stripper bar to force the seed whose lint is held between the roller and bar, away from the lint thus freeing the seed from the lint.

2. A cotton gin, including a supporting 10 frame, a rotatable roller mounted thereon, an unyielding, but adjustable stripper bar arranged to co-operate with the roller, a reciprocating finger bar, and fingers carried by said bar and arranged to force the cot- 15 ton seed from the lint held between the roller and bar, said fingers forming a griddle through which the freed seed may fall.

3. A cotton gin including a supporting frame, a roller mounted thereon, a blade like 20 stripper bar having a beveled edge arranged tangent to the roller, a finger bar, projecting seed forcing fingers carried by said bar and pointing approximately toward the axis of the roller, the points of said fingers 25 clearing the periphery of the roller and edge of the stripper bar, said fingers cooperating with the roller and stripper bar, means for oscillating the finger bar on an axis parallel with the ginning roller, and also 30 means for reciprocating said bar lengthwise with respect to the roller.

4. A cotton gin, including a frame, a roller mounted thereon, and provided with suction passage ways an unyielding but adjustable stripper bar, one edge of which is 35 arranged adjacent the roller a long nozzle in contact with the roller for inducing air suction diametrically through the roller through said passageways, means for confining the zone of suction to the cotton immediately in advance of the bar, a finger bar provided with seed forcing fingers, which co-operate with said roller and stripper bar, means for reciprocating said fingers 40 and means for oscillating them crosswise.

5. A cotton gin, including end frames, a roller mounted thereon with a series of 50 equally spaced longitudinally cored passageways, the diametrically opposite passageways being connected at regular intervals with laterally cored holes passing around the roller shaft, said longitudinal passageways having peripheral ports providing for air suction to go diametrically through the roller, means for driving said roller, a suction nozzle having packing strips lengthwise in contact with the roller surface providing means for creating suction, a stripper bar with one edge adjacent the roller, a 55 lengthwise reciprocating finger bar, projecting seed forcing fingers carried by said bar and means for reciprocating same.

6. A cotton gin including end frames, a roller mounted thereon, consisting of a central spirally fluted cylinder with end nuts 60

and journals and all pairs of two diametrically opposite flutes connected at intervals with laterally drilled holes, a shell pressed on said cylinder with the small drilled holes of the shell in coincidence with the flutes for 70 air suction diametrically through the roller, means for driving said roller, a nozzle with packing strips lengthwise in contact with the roller surface providing means for creating air suction through the roller an unyielding 75 but adjustable stripper bar with one edge adjacent the roller, a lengthwise reciprocating and crosswise oscillating finger bar, projecting seed forcing fingers carried by said bar and means for reciprocating and means 80 for oscillating same.

7. A cotton gin including end frames, a roller mounted thereon having a central spirally fluted cylinder with end nuts for 85 closing the ends of the flutes and end journals, all pairs of diametrically opposite flutes being connected at intervals with laterally drilled holes, a shell pressed on said cylinder having small radial air ducts in coincidence with the flutes providing for air 90 suction diametrically through the roller, means for driving the roller, a nozzle with packing strips lengthwise and in contact with the periphery of the roller, a stripper bar arranged tangential with respect to the 95 roller, means for creating an air suction zone immediately above the stripper bar, a finger bar, projecting seed forcing fingers carried by said bar and pointing toward the axis of the roller the points of said fingers 100 being spaced from the roller and stripper bar, said fingers cooperating with said roller and said stripper bar, means for oscillating said finger bar on an axis parallel with the roller, and means for reciprocating said finger bar lengthwise with respect to the 105 roller.

8. A cotton gin, including two end frames with a connecting spacer in the form of a combined tube and long nozzle and with 110 cored holes in said frames coinciding with the spacer tube means for forcing air blast through same, a roller mounted thereon with a series of equally spaced longitudinally cored passageways the diametrically opposite passageways connected at regular intervals with laterally cored holes, bifurcating around the roller shaft, with small 115 drilled holes into these longitudinal passageways for air suction to go diametrically through the roller, means for driving said roller, suction nozzle with its packing strips in contact with the roller surface providing means for creating suction, a stripper bar with one edge adjacent the roller, a lengthwise reciprocating and crosswise oscillating finger bar, projecting seed forcing fingers carried by said bar and means for reciprocating and oscillating same.

9. A cotton gin including two end frames 120

- with a connecting spacer in the form of a combined tube and long nozzle and with cored holes in said frames coinciding with the spacer tube and means for forcing an air blast through same, a roller mounted thereon consisting of a central slightly spirally fluted cylinder with end nuts and journals and all pairs of two diametrically opposite flutes connected at intervals with laterally drilled holes, a shell pressed on said cylinder with the small drilled holes of this shell in coincidence with the flutes for air suction diametrically through the roller, means for driving said roller, a nozzle with packing strips lengthwise in contact with the roller surface, providing means for creating a suction therethrough, an unyielding but adjustable stripper bar with one edge adjacent the roller, a lengthwise reciprocating and crosswise oscillating finger bar, projecting seed forcing fingers carried by said bar and means for reciprocating and oscillating same.
10. A cotton gin, including a frame, a roller mounted thereon, onto which the seed cotton to be ginned is fed, and formed with diametrical air passageways, a stripper bar, one edge of which is arranged adjacent the roller, said bar being provided to arrest the seed, and the roller operating by friction to carry the lint between it and the bar, means inducing air suction through said passageways, creating air pressure against the cotton in a zone adjacent the bar, a lint flue 35 into which the lint is delivered from the roller, a blast nozzle, through which an air blast is discharged adjacent the roller underneath the stripper bar, and reciprocating fingers movable parallel to the roller and engaging against said seed to strip them free from said lint.
11. A cast metallic gin roller with small
- radial air ducts and a plurality of lengthwise cored passageways spaced apart near the periphery with which said ducts connect, 45 end nuts for closing the ends of said passageways, all pairs of diametrically opposite passageways being connected at regular intervals with laterally cored holes that pass around the roller axis, said holes, passageways, and ducts forming continuous passageways for air suction through the roller.
12. In a cotton gin, a roller formed with a plurality of lengthwise air passageways and a plurality of air ducts extending 55 through the roller at right angles to said passageways, and connecting with the respective passageways at opposite ends, said passageways having peripheral port openings, and a long suction nozzle adjacent said roller whereby a suction zone may be created adjacent the roller opposite the nozzle.
13. In a cotton gin a pair of spaced rollers provided with air ducts an elongated tubular nozzle between the rollers, a partition plate secured to the underside of said nozzle and formed with notches adjacent the nozzle, said nozzle having ports in alignment with said notches, through which a suction may be created through said ducts.
14. In a cotton gin a rocker shaft, a reciprocating finger bar slidable mounted in the shaft, means for rocking said shaft and fingers, and means for reciprocating the finger bar and fingers, lengthwise relative to 75 said shaft.

In testimony whereof I have signed my name to this specification in the presence of two subscribing witnesses.

HENRY E. WERNER.
